MINE SUPPORT

Josef Brand, Duisburg-Hamborn, Germany

Application January 31, 1950, Serial No. 141,447
In Germany June 14, 1949

2 Claims. (Cl. 248—351)

1

This invention relates to supporting caps for use in underground mining.

In the course of modern development of the prop arrangement for underground mining, more and more caps of relatively light metal have been used during recent years. These light metal caps, like the steel caps formerly used, are connected with each other by means of locks and insure a stress-free articulation for the cap on the impact side and thus afford a prop-free working face as is required for modern exploitation methods involving complete mechanization.

This invention concerns a mine installation with light metal caps and aims at improving the application range of such caps. In the types heretofore known, the range of practical usage of caps has been limited to special conditions in view of the relative weakness of light metal and even special alloys as compared to steel as well as the higher costs of such light metals. As a result, a fracture or breakage of a light metal cap and its resulting uselessness has involved a comparatively heavy loss, aside from the dangers involved in its use.

An object is to overcome the difficulties above mentioned and to produce a simple and efficient cap of relatively light metal having the new and improved features of construction and arrangement hereinafter described.

According to this invention, the above shortcomings in mining installations are overcome by a determination of the strength properties, especially of the resistance coefficient of the cap in the X-axis, with respect to the strength properties of the prop supporting the cap in question. This is accomplished in such manner that the resistance coefficient of the cap is greater than that of the prop so that as a result, in case any excess stresses appear, the first to yield is the prop which represents the location of the least resistance, thereby avoiding fracturing the cap. This can be achieved by determining the load limit of the prop at a given cap as well as supplying a corresponding reenforcement for a given prop and, conveniently, by a combination of both methods involving the use of caps representing a relatively great W_s combined with a tolerable expenditure of material.

With the above in view and in accordance with this invention, a cap is produced which fulfills the above requirements in an entirely adequate manner. The basic profile or shape of such cap is that of an I. Its increased resistance coefficient in the axis is achieved by a unique

2

arrangement of ribs which reenforce the vertical portion or web of the I. These ribs extend the entire length of the cap, extending from flange to flange in a zig-zag course and are arranged at an angle of approximately 45° with respect to the longitudinal axis of the cap. Preferably these ribs are arranged on opposite sides of the vertical web of the cap, the ribs on one side being in staggered relation to those on the other side by a distance corresponding to one diagonal. Further strengthening of the cap is accomplished by console-like, triangularly arranged stays or webs arranged between the web of the cap and the flanges at spaced intervals throughout the length of the cap, such webs alternating at the upper and lower flanges and being staggered with respect to each other by intervals corresponding to a diagonal.

A cap is thus produced having exceedingly favorable resistance coefficient and of much lighter weight, in spite of the ribbed construction, than other special shapes heretofore used such as box profiles. Within the range of the basic idea underlying this invention as hereinbefore outlined, such cap can be used in connection with mass-produced props of standard design having normal load capacity and sinking resistance, due to the fact that its resistance coefficient is greater than that of such props.

While the measures above described suffice, in order to prevent the fracture of the cap and thus its total destruction, there remains, nevertheless, the liability of damage threatening locations where the caps are subjected locally to a particularly great stress.

These caps are provided as in the case of the standard steel caps, with complementary parts of locks of two adjoining caps for connecting them by means of an articulated bolt. By means of intermediary elements such as wedges, etc., this connection bears, without buckling, against the surfaces or special attachments to the caps for the purpose of a stress-free articulation. Such connection results in a relatively great stress on the parts engaged by the connecting elements such as bolts and wedges. This may result in danger especially when the stress-free articulated cap is exposed at the end to a greater suspension pressure. In caps of standard design, this stress may result in local damage and breakage at the lock parts. Consequently, an expensive cap would likewise be rendered useless.

Further, in accordance with this invention, such danger is avoided by protecting the especially stressed parts of the lock by a screw or shield of a

material which is less expensive but has relatively high tensile properties such as sheet steel. These screens or shields absorb the stresses resulting from the connecting elements such as bolts and wedges and transmit them in a harmless fashion to the relatively light metal of the cap. Manifestly, in case of damage, the sheet steel screens or shields may be readily replaced.

For purposes of illustration but not of limitation, an embodiment of the invention is shown on the accompanying drawings. In the drawings, the basic concept of this invention is illustrated in connection with articulated caps. The caps are shown connected to each other by means of an articulated bolt and the stress-free articulated cap is secured in position of use by a wedge driven into place between the lock parts of adjacent caps. In this structure, a pulling stress may be imposed on the supporting end of the articulated cap arrangement at any desired angle without liability of damage or fracture.

In the drawings,

Figure 1 is a side elevation of an end portion of a cap;

Figure 2 is a longitudinal sectional elevation showing a pair of caps connected together, the left-hand cap constituting a section on the line A—B of Figure 1; and

Figure 3 is a vertical sectional view substantially on the line C—D of Figure 1.

Referring to the drawings, a cap *a* is shown connected to a cap *b*. A bolt or pin *e* is inserted through registering apertures in the forked end *d* of the cap *b* and through an opening *c* in the cap *a*. Both caps *a* and *b* are I-shaped in cross section and are reinforced by ribs. As shown particularly on Figure 1, ribs *g* are arranged in zig-zag fashion and are integral with and project outwardly from the web or stay *f*, from flange to flange. In addition, the I-shape is reinforced by console-like triangular webs *h* which are arranged between the flange and web of the cap. The ribs *g* are arranged on both sides of the web of the cap and are staggered with respect to each other by a distance corresponding to a diagonal. As a result, the ribs *g* which oppose each other on opposite sides of the web of the cap, are in crossing relation. Similarly, the consoles or webs *h* are arranged alternately at the upper and lower flanges of the cap and staggered in corresponding manner relative to each other on both sides of the web of the cap. Consequently, wherever an upper console or web *h* exists on one side of the web of the cap, a lower web or console is disposed on the other side.

The end of the cap *a* is protected from the lock pin *e* by means of a substantially U-shaped shield or screen *i* of relatively tough sheet metal such as steel. As indicated at *k*, the end portion of the cap *a* is recessed to receive the shield *i* so that the outer surface of the shield is flush with the adjacent portion of the cap *a*, thereby to obviate any projecting edge portions. The shield *i* may be secured in place by any means well-known to those skilled in this art. The shield *i* is provided with apertures to register with the transverse aperture on the end of the cap *a*. This arrangement is such that all stresses emanating from the bolt are taken up by the shield.

As shown, a bracing wedge *m* engages both caps *a* and *b* for militating against bending of the joint and to afford a stress-free articulation. The wedge bears against the front end *n* of the shield *i*, which, as shown, is oblique with respect to the axis of the pin *e*, for example, the latter being disposed at substantially right angles to the longitudinal axis of the cap *a*. The opposite side of the wedge *m* bears against a counter surface *o* on the forked end portion of the cap *b*. If desired, the forked end portion *d* of the cap *b* may be similarly provided with a sheet steel shield.

It is to be understood that numerous changes in details of construction, arrangement, design and choice of materials may be effected without departing from the spirit of the invention especially as defined in the appended claims.

What I claim is:

1. A cap for subsurface mining comprising an elongate beam of relatively light metal and of substantially I shape in cross section, ribs integral with the web of said beam and disposed in zig-zag fashion throughout the length thereof, said ribs being arranged on each side of the web with the ribs on one side in staggered relation with respect to the ribs on the other side, and integral console-like reinforcements of substantially triangular shape on opposite sides of said beam and connected respectively to a flange and the web of the beam, said reinforcements being spaced from each other a distance equal to the length of one rib and so arranged that a reinforcement on the upper portion of one side of the beam faces a reinforcement on the lower portion of the other side of the beam.

2. A cap for subsurface mining comprising an elongate beam of relatively light metal and of substantially I shape in cross section, ribs integral with the web of said beam and disposed in zig-zag fashion throughout the length thereof, said ribs being arranged on each side of the web with the ribs on one side in staggered relation with respect to the ribs on the other side, and integral console-like reinforcements of substantially triangular shape on opposite sides of said beam and connected respectively to a flange and the web of the beam, said reinforcements being spaced from each other a distance equal to the length of one rib and so arranged that a reinforcement on the upper portion of one side of the beam faces a reinforcement on the lower portion of the other side of the beam and the position of adjacent pairs of reinforcements is reversed.
